APPARATUS FOR STRIPPING BARK FROM
STEP-BY-STEP ADVANCED SAWMILL EDG-
INGS OR SLABS

John R. Roberts, De Valls Bluff, Ark.

Application September 18, 1947, Serial No. 774,700

14 Claims. (Cl. 144—208)

1

This invention relates to machines for removing the bark from slabs, edgings and the like which have been sawed off from logs in sawmills and it has for its principal purpose to produce a simple and sturdy automatically operating apparatus which performs the desired operation reliably to such an extent that the resulting product may be used for the making of wood pulp.

It is one of the principal objects of the invention to provide an apparatus of this type, which obtains the desired result by advancing the slab to be freed from the bark toward chisels, knives or teeth performing this operation in a step by step advance, each step resulting in an advance over a limited distance.

It is a further object of the invention to provide simple means for the automatic advance of the slabs in steps such means including gripping means adapting themselves automatically to the shape or configuration of the slab.

It is a further object of the invention to provide means for automatically applying and removing the debarking chisels, knives or teeth when the slab moves into the proper position.

It is a further object of the invention to control these automatic means, by a movable member actuated by the slab itself during its advance.

It is a further object of the invention to automatically remove the debarking chisels, knives or teeth from the slabs when they get stuck so that the slab carries them with it or is stopped by them.

Further objects will be apparent from the following detailed specification.

The invention is illustrated in the accompanying drawing showing one embodiment thereof by way of example. This example will illustrate the constructive principle and also one mode of application of the machine, but it does not illustrate modifications of the constructive details many of which, once the principle and the problem to be solved have been explained, will be more or less within the range of the skill of the expert. Modifications of the inventions are therefore not necessarily departures from the essence of the invention.

In the accompanying drawings:

Figure 1 is a plan view of the machine.

Figure 2 is an elevational side view of the machine.

Figure 3 is an elevational sectional view, the section being taken along the plane of symmetry.

Figures 4 and 5 are sectional elevational end views the sections being taken along lines 4—4 and 5—5 of Figure 1, respectively.

2

Figure 6 is an elevational sectional view of a detail.

Figure 7 is a sectional plan view of a detail.

Figure 8 is an elevational view of a detail.

Figure 9 and Figure 10 are perspective views of details.

In sawmills it is customary to remove bark carrying slabs and edgings from logs. The slabs have usually approximately the shape of a cylinder segment, with the round surface carrying the bark. As the slab has been cut away from the outer surface of the log it consists essentially of valuable pulp material, and is even of special value for the making of cellulose as it is the portion richest in sap. It will therefore be clear that repeated attempts have been made to make this material available for the wood pulp manufacturer by removing the bark which is not usable.

The principal purpose of the invention therefore consists in providing a debarking machine which is specially adapted for slab debarking work.

The slab debarker according to the invention comprises a frame 11 on which all the parts and mechanisms are mounted.

It carries fixedly mounted slab clamping means 12 and guide rails 13 for a reciprocating carriage 14 which carries a reciprocating feeding mechanism. It moreover carries the debarking mechanism generally indicated at 50 and described below.

The fixed slab clamping and holding mechanism consists of a plurality of teeth holding supports 15, one of said supports being arranged near the admission end of the frame. Each support 15 is U-shaped and has a bottom piece 16 on which the slab rests and two lateral upstanding shields 11. On these shields a frame 18 is mounted carrying a cross bar 19.

The shields hold an axle 21 serving as a pivot or fulcrum for a row of clamping teeth 20 which may turn around said axle and are therefore provided with bores. A large number of clamping teeth 20 are arranged side by side, each of which is individually movable. Each clamping tooth is provided with an eye 22 at its upper end, which holds the end of a coiled spring 23 the other end of which is held in a hook carried by the cross bar 19 of the frame 18. Therefore each clamping tooth is individually under spring tension and is pressed with its free end against the bottom on which the slab rests. The clamping teeth at their downwardly directed ends 24 are preferably pointed and provided with cutting edges which engage the bark covered surface of the slab and which are adapted to hold it firmly.

In front of the fixed slab clamping mechanism at the admission end a number of rollers 25 (Figure 1) are arranged (one being merely shown in the drawing) over which the slab is moved when it enters the U-shaped support 15 with its flat face resting on the bottom. Near the point where the slab enters two strong resilient curved guides 26 are mounted, which engage the sides of the slabs and guide it towards the central or middle portion of the clamping and feeding mechanism. The resilient guides 26 are adjustable and may turn around pivots 27. They are provided with ears 28 engaged by strong coiled springs 29 pressing them inwardly towards the middle zone.

The guide rails 13 are longitudinally disposed along the frame 11 and they form a slideway for the carriage 14 of the reciprocating feeding mechanism 34. This mechanism consists of a plurality of U-shaped supports 35, similar to the supports 15 of the fixed clamping mechanism, but mounted on the carriage 14, each consisting of a bottom piece 37 on which the flat surface of the slab may rest and of two shields 38. The latter carry an axle 39 forming a fulcrum for the feeding teeth 40. A row consisting of a large number of such feeding teeth is mounted side by side on the axle, each tooth having a bore through which the axle passes. The feeding teeth are therefore individually movable and may occupy different positions so as to adapt themselves to the shape of the slab. Each tooth 40 is provided with an eye 41 at its upper end. The support 35 moreover carries a frame 36 provided with a cross bar 42. A row of coiled springs 44 is inserted between the eyes 41 of each tooth 40 and hooks projecting from the cross bar 42. The coiled springs draw the ends 45 of teeth 40 towards the work piece resting on the bottom piece 37. The slabs are thus firmly gripped. It will be noted that the clamping teeth are held in an inclined position and that they have pointed cutting edges 45 adapted to penetrate into and to thereby firmly engage the bark covered upper surface of the slab resting on the bottom pieces 37.

The carriage 14 is provided with guide sleeves 46 which slide on the guide rails 13. In the example shown the rails are cylindrical rods which are completely encircled by the sleeves.

Each carriage, as has been mentioned, is provided with a plurality of supports 35 carrying feeding teeth, two such supports being shown in the example illustrated.

The reciprocating movement of the carriage is produced by a driving mechanism comprising a driving pulley 60 mounted on the rear end of the frame 11 on a shaft 61. This driving pulley is driven by a belt or cable or in any other appropriate manner (not shown) from a motor of any type.

The shaft 61 is journaled in bearings 59 and carries a pulley 63 driving, by means of a belt transmission 62, the pulley 64 on shaft 65. A roller 66 is provided for tensioning the belt; this roller may be adjustable for instance by mounting it on rockable arms. Shaft 65 carries the two driving disks 67 arranged on each side, each provided with a driving pin 68 actuating a pitman rod 69 which is pivoted to a link 70 fulcrumed at 71 on a pivot carried by the carriage frame 11. The other end of the link 70 carries a further link 72 pivoted at 73 to the carriage. By virtue of the double disk driving arrangement the carriage is thus operated on both sides by the links 70, 72.

The debarking mechanism generally indicated at 50 is carried by uprights 75 projecting upwardly from a U-shaped support 76 which is provided with guiding sleeves 77 sliding on the guide rails 13. The support 76 may be integrated with the U-shaped support 76' of one of the fixed slab clamping devices 12' which in this case is also provided with guiding sleeves 77' sliding on rail 13 (Figure 3). In this case the two supports 76 and 76' form a single U-shaped unit.

The uprights 75 are pivoted on the supports 76 by means of pivots 79. Their position together with the position of the parts carried by them is adjusted by a pitch adjustment device 80 which consists of a rod 81 pivoted to the uprights and passing through a bore in a laterally projecting ear 82. The rod is threaded and either may engage threads in the bore of the ear or may pass freely through said bore and be provided with nuts 82' on both sides of the ear permitting adjustment of the effective length of the rod, which is that portion of the rod located between the ear and the point at which it is pivoted to the upright 75. It will be clear that in this way the inclination of the upright towards the vertical may be finely adjusted.

The uprights 75 are provided with slots 102 for a purpose mentioned below and are joined by a transverse bar 83 and by transverse holding plates 84, 84, 85 which are so disposed that they enclose and hold between them the entire series or row of debarking chisels or teeth 90. These debarking teeth or chisels are shown separately in Figure 10. They are of a rectangular or square cross section and are provided with slots 91. At their ends 92 they are pointed and cutting edges 93 are formed which are applied against the bark covered surface of the slab. Each tooth or chisel 90 is moreover provided with an eye 94 into which a coiled spring may be hooked.

The teeth 90 are aligned between the two uprights 75 on one hand and between the holding plates 84, 84 and 85 on the other hand. They are in frictional contact with each other and are freely movable in an axial direction, but are otherwise guided laterally by means of the uprights and holding plates. The uprights guide merely the two outer members of the series, but on account of the alignment of the teeth and because the space between the uprights is filled completely and snugly they act as each other's guiding surfaces, if moved separately. When the teeth are aligned between the uprights the slots 91 are also aligned.

On the outside the uprights 75 on both sides carry supporting shields 95 joined to them by bolts with jam nuts in order to be able to remove the structure carried by the shields for repairs. In the example shown, the supporting shields are arranged at a small distance from the uprights so that the heads of the pitch adjustment rod, the vertical portions of the U-shaped supports 76 and other parts may be arranged between them. Each supporting shield carries two opposed hydraulic or air cylinders 96, 97 provided with pistons 98 (visible in Figure 6 only) which are joined by a common piston rod 99. The pistons are positively operable on either stroke by the pressure fluid admitted into one of the cylinders. The two piston rods 99 on the sides of the debarking mechanism are joined by a yoke bar 100 which passes through slots 101 in the shields, through the slots 102 in the uprights 75, already mentioned above, which are aligned with the slots 101

and through the slots 91 of the debarking chisels or knives 90. At each end the yoke bar 100 is provided with a head 103 fixed to the piston rods 99, and with a projecting wing or bracket 104. Moreover a frame 106 of U-shape depending from the heads and arranged in substantial parallelism with the row of chisels or debarking knives 90 at a small distance behind the same is fixed to said heads by means of lugs 105, projecting rearwardly from said heads.

The transverse or cross bar member of the U-shaped frame 106 serves as a support for a series of coiled springs 210. Each of said springs is allotted to one of the debarking chisels or knives 90 and is attached to said cross bar of the frame on one hand and to the eye 94 on the other hand. It will thus be seen that if pressure fluid is admitted to one cylinder, while the other cylinder is connected with the exhaust, the piston rod 99, the yoke bar 100 and the frame 106 with all the 20 springs are forced down, the relative position of these parts remaining unchanged.

The wing bracket 104 carries a chain or cable holder 107 to which a cable 108 is attached. The cable is wound on a drum 109 which is fixed on a shaft 110 carried in journal brackets 111. Further drums 112 are keyed on said shaft and cables 114 are wound and attached to them. These cables are attached on their other ends to coiled springs 115 which are secured to the upper fixed holding plate 84. This plate may preferably be formed by an angle, on the projecting flange of which the ends of the coiled springs are fastened. It will therefore be understood that when the piston and yoke bar move down the springs 115 are tensioned and return the piston rod and yoke bar as soon as the pressure of the pressure fluid on the upper piston drops.

The two cylinders 96, 97 are operated by a pressure fluid such as air or a hydraulic fluid according to circumstances.

Assuming the pressure fluid to be air, suitable air lines 120, 121 connect the two cylinders on both sides respectively and the line 120 connecting cylinders 96 of both sides is supplied by air line 122 leading to control valve 125 on one side while connecting line 121 for the two cylinders 97 is supplied by line 123 leading from the control valve 130 on the other side. Both valves are supplied by a common bifurcated supply line 128.

The control valves themselves are of the customary type, for instance of the type provided with a piston establishing communication between bores or channels in communication with the cylinder controlled by the valve and the admission line and discharge line or opening (not shown) respectively and only the outside of the valves is shown. They are controlled by a piston valve rod 126, 127 respectively, each being under the tension of a spring 129, 139 respectively. The piston valve rod 126 is provided with a forked head 132 through which a trip bar 133 passes.

The automatic control of the valve is effected by means of a slab operated trip plate 140 which is mounted on an axle 141 held within the frame 11 and which projects upwardly through a slot 142 in the bottom part 78 of the U-shaped support 76 below the debarking chisels or knives. The trip plate is preferably weighed by means of weight 143. Under the influence of the weight it adopts an inclined position as shown in Figure 3 with its upper edge above the support 76 so that a slab sliding into position on the support will depress said upper end and will turn the plate 140 and the axle 141.

The trip bar 133 is fixedly attached to that part of the axle 141 which projects outwardly through the frame 11. It will therefore be clear that when a slab being pushed along the support, reaches the position below the debarking chisels, it depresses the tripping plate and thereby turns the plate with its axle and with the tripping bar 133 attached to it. The tripping bar pushes back the forked head 132 of the valve piston rod 126 and 10 opens the valve so that air is admitted to piston 96 to force the debarking knives down on the slab. After the slab passes the tripping plate 140, valve 125 is closed by spring 129, air pressure on piston 125 ceases so that springs 115 unwind cables 114 and rotate shaft 110 to wind up cables 108, which raise yoke bar 100 and thus lift the chisels out of the path of an oncoming slab.

It has already been described that the support 76 carrying the uprights 75 and the debarking mechanism is movable on the rails 13 by means of the sleeves 77, such movement being independent of the reciprocating carriage movement produced by the drive pulleys. This movement is permitted because the chisels or knives might dig into the slab in such a manner occasionally that they cannot detach themselves, but get stuck. In this case the slab advanced by the carriage movement would move the entire support 76 with its machinery on the rail 13. This movement is limited and is moreover utilized for detaching the chisels from the slabs. The slide support 76 is provided with projecting brackets 144 entering into suitable heads 145 of draw bars 146 passing through bores in spring retainers 148. Between said spring retainers and the end of the draw bars 146 provided with suitable spring pressing disks, strong springs 147 are inserted, which provide a suitable resistance against shifting of the unit 50 on the rails 13.

Moreover the head 145 located in front of valve 130 also acts as an actuator or control member for said valve. When the unit is moved by the slab it strikes against the end 149 of piston valve rod 127 and thereby actuates the piston in valve 130 so that air is admitted to the cylinders 97 through pipes 123 and 121. The pistons 97 will push the piston rods 99 upwardly and will therefore disengage the debarking chisels from the slabs. The springs 147 then pull the unit 50 back, and the piston of the valve 130 is returned by spring 139, thus permitting the pressure fluid to escape.

The slab debarking operation has partly already been described and may be summarized as follows.

The slabs or edgings are pushed in over the rollers 25 and are held in a middle position by the resilient guides 26. They advance pushing the teeth 20 of the fixed clamping device 12 upwardly. These teeth are inclined and rest on the bark of the slab, along its entire contour, whatever the shape of contour as the teeth are individually movable and will adjust themselves to this contour which is normally approximately a part of a cylinder. The slab advances further and comes under the teeth 40 of the reciprocating feeding mechanism 34 driven by the pulleys and finally under the debarking mechanism 50. Considering now merely the automatic operation the tripping plate 140 is turned when the slab reaches the position below the chisels 90 and the valve 125 is operated. This lowers the debarking chisels, as air is admitted to cylinders 96, thus lowering the yoke bar 100 and the row of chisels. As each chisel or knife is held by its own coil spring 110 the chisels or knives adjust

themselves perfectly to the contour of the slab. Moreover, the angle between the chisels and the slab may be adjusted by means of the pitch adjustment bars.

The carriage 14 is meanwhile reciprocated by means of pulleys 60 and 64 and pitman rods 69, driven by disks 67 and by means of links 10 and 12. During the forward movement of the carriage the slab advances with the carriage with the chisels slicing off the bark from the slab during this stroke. During the return movement of the carriage the fixed clamping devices 12 by means of their teeth movable around axle 21, prevent any backward movement of the slab, as the teeth on account of their inclined position and pointed cutting edges penetrate deeper and deeper into the slab if such movement is attempted. The carriage therefore moves back while the slab remains stationary but carries the slab forward again with the next stroke, the teeth 40 holding the slab firmly on the carriage during this forward movement. Again the chisels slice off the bark and the operation is repeated.

The operation when the chisels get stuck in the slab has already been described.

It is therefore seen that the bark is removed by a series of short timed step by step advance movements with pauses between them. It has been found by experience that this method is the best mode of removing between 85% to 100% of the bark of the slabs. As a removal of 80% of the bark will make the slabs fit for the making of wood pulp, the product of the machine will practically be fully utilizable.

It will be understood that the number of clamping and gripping devices used in the machine depends largely on circumstances and on the nature and presence of auxiliary appliances for feeding, removal and other operations. The number shown is necessary in cases in which the slab is supposed to be fed by hand or by auxiliary appliances to a certain point in front of the debarking structure and to be delivered at another point in the rear of the debarker, the machine taking care of the movement between these two points. Manifestly the last reciprocating gripping device defines the last mentioned point. In other respects the number and distribution of the clamping and gripping devices is subject to change according to circumstances.

The invention has been described by giving specific examples of the details used. It has to be emphasized however that the specific designs of the details mentioned in the foregoing specification are not connected with the invention in such a way that a change in the details will entail a departure from what is considered as the invention.

Having described the invention, what is claimed as new is:

1. In a slab debarking machine, a frame, a series of independent debarking chisels, each capable of being pressed against the slab independently of the other and arranged in a series disposed transversely with respect to the slab, means for advancing the slab step by step toward the debarking chisels, said means comprising a reciprocating slab carrying carriage, slab gripping devices mounted on said carriage and comprising a series of individually movable inclined teeth, separate means for pressing each of said teeth against the slab for holding said slab on said carriage and for gripping said slab when the carriage advances toward the debarking chisels, while releasing the slab during the re-

turn movement of the carriage, clamping devices fixed on the frame, each comprising a number of individually movable inclined teeth, means for pressing the teeth separately against the slab, for clamping said slab and holding it during the return movement of said carriage.

2. In a slab debarking machine, a frame, a series of independent debarking chisels each capable of being pressed against the slab independently of the other and arranged in a series disposed transversely with respect to the slab, means for advancing the slab step by step toward the debarking chisels, said means comprising a reciprocating slab carrying carriage, guiding rails 10 along said frame, guiding sleeves on said carriage slidable on said rail, driving means for said carriage for producing a reciprocating movement, slab gripping devices mounted on said carriage and comprising a series of individually movable inclined teeth, separate means for pressing each of said teeth against the slab for holding said slab on said carriage and for gripping said slab when the carriage advances toward the debarking chisels, while releasing the slab during the return movement of said carriage, clamping devices fixed on the frame, each comprising a number of individually movable inclined teeth, means for pressing the teeth separately against the slab, for clamping said slab and holding it during the return movement of said carriage.

3. In a slab debarking machine, a frame, means for advancing the slab step by step, said means comprising a reciprocating slab carrying carriage, slab gripping devices on said carriage each including individually movable inclined teeth, separate means for pressing each of said teeth against the slab for gripping and holding the latter on the carriage during the advance of the carriage, while releasing said gripping action during the return movement, further gripping and clamping devices fixed on said frame, each including a number of individually movable inclined teeth, means for pressing the same against the slab for holding the slab during the return movement of the carriage, a series of debarking chisels aligned in a transverse row with respect to the direction of advance of the slab, means for holding said series of aligned debarking chisels above said slab, means for moving the entire series of debarking chisels toward the slab and away from the same, and separate means for pressing each individual chisel toward the slab when the series has been moved into contact with the same.

4. In a slab debarking machine, a frame, means for advancing the slab step by step, said means comprising a reciprocating slab carrying carriage, slab gripping devices on said carriage each including individually movable inclined teeth, separate means for pressing each of said teeth against the slab for gripping and holding the latter on the carriage during the advance of the carriage, while releasing said gripping action during the return movement, further gripping and clamping devices fixed on said frame, each including a number of individually movable inclined teeth, means for pressing the same against the slab for holding the slab during the return movement of the carriage, an upstanding chisel 60 supporting structure mounted on said aforesaid frame, including lateral and transverse guiding members forming a guiding framework, a series of debarking chisels aligned and movable within said guiding framework and movable as a series 70 toward and away from said slab, separate means

for pressing each debarking chisel downwardly into the lowermost position within the series and into contact with the slab, and fluid pressure operated means for moving the series of chisels downwardly toward the slab and upwardly away from the slab.

5. In a slab debarking machine, a frame, means for advancing the slab step by step, said means comprising a reciprocating slab carrying carriage, slab gripping devices on said carriage each including individually movable inclined teeth, separate means for pressing each of said teeth against the slab for gripping and holding the latter on the carriage during the advance of the carriage, while releasing said gripping action during the return movement, further gripping and clamping devices fixed on said frame, each including a number of individually movable inclined teeth, means for pressing the same against the slab for holding the slab during the return movement of the carriage, an upstanding debarking chisel support, mounted on said aforesaid frame, provided with lateral uprights and transverse members forming a guiding frame, a series of debarking chisels aligned and movable within said guiding frame and movable as a series toward and away from said slab, separate means on said guide frame for pressing each debarking chisel toward a slab when brought into operative position on the same, pairs of opposing cylinders, each pair of cylinders being joined by a common piston rod operated alternatively by fluid pressure within the cylinders, a transverse member connected to said common piston rod for producing the joint upward and downward movement of the series of chisels and means for supplying the cylinders alternatively with a pressure fluid.

6. In a slab debarking machine, a frame, means for advancing the slab step by step, said means comprising a reciprocating slab carrying carriage, slab gripping devices on said carriage each including individually movable inclined teeth, separate means for pressing each of said teeth against the slab for gripping and holding the latter on the carriage during the advance of the carriage, while releasing said gripping action during the return movement, further gripping and clamping devices fixed on said frame, each including a number of individually movable inclined teeth, means for pressing the same against the slab for holding the slab during the return movement of the carriage, an upstanding chisel supporting structure pivotally mounted on said frame, and provided with lateral uprights and transverse members forming a guiding framework, means for adjusting the angular position of said chisel supporting structure with respect to the direction of advance of the slab, a series of debarking chisels aligned and movable within said guiding framework and movable as a series toward and away from said slab, separate means for pressing each debarking chisel downwardly into the lowermost position within the series and into contact with the slab, and fluid pressure operated means for moving the series of chisels downwardly toward the slab and upwardly away from the slab.

7. In a slab debarking machine, a frame, means for advancing the slab step by step, said means comprising a reciprocating slab carrying carriage, slab gripping devices on said carriage each including individually movable inclined teeth, separate means for pressing each of said teeth against the slab for gripping and holding the latter on the carriage during the advance of the carriage, while

releasing said gripping action during the return movement, further gripping and clamping devices fixed on said frame, each including a number of individually movable inclined teeth, means for pressing the same against the slab for holding the slab during the return movement of the carriage, an upstanding debarking chisel supporting structure mounted on the aforesaid frame and provided with lateral uprights and transverse members forming a guiding frame, said lateral uprights being provided with slots, a series of aligned debarking chisels each provided with a slot and each movable within said guiding frame, individual means associated with and carried by said guiding frame for keeping each member of the series under pressure, cylinders mounted on said chisel supporting structure and containing fluid under pressure for operating piston rods, a transverse yoke member secured to said piston rods and passing through the slots of the uprights and of the chisels to move the entire series, and resilient means associated with said guiding frame and tensioned when the entire series is moved in one direction.

25 8. In a slab debarking machine, a frame, means for advancing the slab step by step, said means comprising a reciprocating slab carrying carriage, slab gripping devices on said carriage each including individually movable inclined teeth, separate means for pressing each of said teeth against the slab for gripping and holding the latter on the carriage during the advance of the carriage, while releasing said gripping action during the return movement, further gripping and clamping devices fixed on said frame, each including a number of individually movable inclined teeth, means for pressing the same against the slab for holding the slab during the return movement of the carriage, an upstanding chisel supporting structure movably and slidably mounted on said frame, said structure comprising lateral and transverse guiding members and forming a guiding framework, a series of debarking chisels aligned and movable within said guiding framework and movable as a series toward and away from said slab, separate means for pressing each debarking chisel downwardly into the lowermost position within the series and into contact with the slab, and fluid pressure operated means for moving the series of chisels downwardly toward the slab and upwardly away from the slab.

40 9. In a slab debarking machine, a frame, means for advancing the slab step by step, said means comprising a reciprocating slab carrying carriage, slab gripping devices on said carriage each including individually movable inclined teeth, separate means for pressing each of said teeth against the slab for gripping and holding the latter on the carriage during the advance of the carriage, while releasing said gripping action during the return movement, further gripping and clamping devices fixed on said frame, each including a number of individually movable inclined teeth, means for pressing the same against the slab for holding the slab during the return movement of the carriage, guiding rails mounted on said frame, guiding sleeves on said carriage sliding on said rails, an upstanding chisel supporting structure having guides slidable on said guide rails, said guides mounting said chisel supporting structure for movement independent of said carriage, said chisel supporting structure including lateral and transverse guiding members forming a guiding framework, a series of debarking chisels aligned and movable within said guiding framework and

45 50 55 60 65 70 75

movable as a series toward and away from said slab, separate means for pressing each debarking chisel downwardly into the lowermost position within the series and into contact with the slab, and fluid pressure operated means for moving the series of chisels downwardly toward the slab and upwardly away from the slab.

10. In a slab debarking machine, a frame, means for advancing the slab step by step, said means comprising a reciprocating slab carrying carriage, slab gripping devices on said carriage each including individually movable inclined teeth, separate means for pressing each of said teeth against the slab for gripping and holding the latter on the carriage during the advance of the carriage, while releasing said gripping action during the return movement, further gripping and clamping devices fixed on said frame, each including a number of individually movable inclined teeth, means for pressing the same against the slab for holding the slab during the return movement of the carriage, a chisel supporting structure mounted on said frame, including lateral and transverse guiding members forming a guiding framework, a series of debarking chisels aligned and movable within said guiding framework and movable as a series towards and away from said slab, fluid pressure operated means for moving the series of aligned chisels, valve means for controlling the pressure fluid supply and means operated by the slab for controlling said valve means.

11. In a slab debarking machine, a frame, means for advancing the slab step by step, said means comprising a reciprocating slab carrying carriage, slab gripping devices on said carriage each including individually movable inclined teeth, separate means for pressing each of said teeth against the slab for gripping and holding the latter on the carriage during the advance of the carriage, while releasing said gripping action during the return movement, further gripping and clamping devices fixed on said frame, each including a number of individually movable inclined teeth, means for pressing the same against the slab for holding the slab during the return movement of the carriage, a chisel supporting structure mounted on said frame, including lateral and transverse guiding members forming a guiding framework, a series of debarking chisels aligned and movable within said guiding framework movable as a series toward and away from said slab, fluid pressure operated cylinders for moving the series of aligned chisels toward the slab, a valve for controlling the pressure fluid supply to the cylinders, operating means for the same, a rockable tripping plate arranged beneath the chisel supporting structure, means for connecting said tripping plate with the operating means of the valve, to control automatically the downward movement of the aligned chisels.

12. In a slab debarking machine, as claimed in claim 9, and means to control the fluid pressure means that move the series of chisels upwardly and away from the slab, said control means being operated by the slideable chisel supporting structure when the latter slides independently along the guiding rail.

13. In a slab debarking machine, as claimed in claim 9, means for limiting the independent sliding movement of the chisel supporting structure comprising lateral brackets projecting from said structure through the frame, and spring means fixed on the frame attached to said brackets and opposing movement of said structure in the slab advancing direction.

14. In a slab debarking machine, a frame, means for advancing the slab step by step, said means comprising a reciprocating slab carrying carriage, slab gripping devices on said carriage each including individually movable inclined teeth, separate means for pressing each of said teeth against the slab for gripping and holding the latter on the carriage during the advance of the carriage, while releasing said gripping action during the return movement, further gripping and clamping devices fixed on said frame, each including a number of individually movable inclined teeth, means for pressing the same against the slab for holding the slab during the return movement of the carriage, a chisel supporting structure mounted on said frame, including lateral and transverse guiding members forming a guiding framework, a series of debarking chisels aligned and movable within said guiding framework and movable as series towards and away from said slab, said chisel supporting structure being slideable on said frame, means for limiting said sliding movement of the chisel supporting structure including brackets and springs attached thereto, cylinders containing fluid pressure operated pistons for producing a downward movement of the series of aligned chisels and further cylinders containing fluid pressure operated pistons for producing an upward movement of said series, valve means for controlling the admission of pressure fluid to said cylinders, actuating means for said valve means, the actuating means for the valve controlling the upward movement of the series of chisels being engaged and operated by the brackets when the chisel supporting structure slides relatively to the frame and approaches one limit of the sliding motion.
